ELMER S. GROSS, OF RACINE, WISCONSIN.

TOOL REST OR SUPPORT.

1,369,424.

Specification of Letters Patent.

Patented Feb. 22, 1921.

Application filed August 30, 1919. Serial No. 320,881.

To all whom it may concern:

Be it known that I, ELMER S. Gross, a citizen of the United States, and resident of Racine, in the county of Racine and State of Wisconsin, have invented new and useful Improvements in Tool Rests or Supports, of which the following is a description, reference being had to the accompanying drawings, which are a part of this specification.

10 The present invention relates to certain new and useful improvements in tool rests or supports, and, while I have illustrated the same, in the accompanying drawing, as attached to a micrometer, it will be appreciated that the same may be employed in connection with various other types of tools.

15 In using tools having a fine adjustment, great difficulty is experienced in that, in placing the tool on a work bench or in removing the same therefrom, the adjustment is generally disturbed by the contacting of the adjusting thimble with the surface of the work bench. Hence, with this inherent objection in mind I devised my tool rest 20 or support which has for one of its objects to provide means connectible to a tool for supporting the same, when not in use, so that its adjusting thimble will not engage with the surface of the work bench when 25 the tool is either placed thereon or removed therefrom.

Another object of the present invention is to provide a tool rest or support in which the supporting members are movable to a 30 position extending laterally from the sides of the tool or to a position adjacent the sides of the tool.

35 A further object of this invention is to provide a tool rest or support including supporting members movable to either of two positions and means for retaining the members under tension in either of said two positions.

40 A still further object of the invention is to provide a tool rest or support of the class and for the purposes described which may be secured to tools now in use or to tools at the time of their manufacture.

45 With the above and other objects in view which will appear as the description proceeds, by invention resides in the novel construction, combination and arrangement of parts substantially as hereinafter described and more particularly defined by the appended claims, it being understood that such

changes in the precise embodiment of the herein disclosed invention may be made as come within the scope of the claims.

In the accompanying drawing I have illustrated one complete example of the physical embodiment of my invention constructed according to the best mode I have so far devised for the practical application of the principles thereof, and in which:

Figure 1 is a side plan view of a micrometer having my invention attached thereto. 65

Fig. 2 is a sectional view therethrough taken on the line 2—2 of Fig. 1.

Fig. 3 is an end view of a micrometer having a slightly modified form of my invention attached thereto, parts of the micrometer being broken away and in section. 70

Fig. 4 is a side plan view of one end portion of a micrometer illustrating that form of my invention depicted in Fig. 3, and 75

Fig. 5 is a transverse sectional view therethrough taken on the line 5—5 of Fig. 4.

Referring now more particularly to the accompanying drawings, the numeral 6 designates a tool, in the present instance being a micrometer, to which my invention is secured by means of a clip or other suitable attaching member 7.

In Figs. 1 and 2, I have shown the clip member as being connected with the central portion of the tool 6 by means of a securing screw 8 which passes through the tool 6 and is threaded into the opposite side of the clip. The clip 7 is substantially U shaped and has struck from its sides a pair 90 of centrally disposed resilient tongues or lips 9 and formed in the strips adjacent the tongues 9 are alined bulged or enlarged portions 10 forming bearings for receiving the inner ends of a pair of supporting members 95 or arms 11. The arms 11 each have two flattened sides 12 adjacent the tongue members 9 and tensioning means for retaining the arms 11 in either extended position or folded position are thus provided. As the 100 clip 7 is preferably of spring steel, brass or the like, when the arms 11 are in extended position, as depicted in Figs. 1 and 2, one of the flattened sides 12 of each arm will be engaged against the adjacent tongue 9 and when the arms 11 are moved to a position folded against the sides of the tool 6, the corner formed by the flattened sides 12 must cam over the tongues 9 and thus spring 105 the sides of the clips 7 from the sides of 110

the tool to bring the other flattened side of each arm into contact with its adjacent tongue 9.

In that form of my invention depicted in 5 Figs. 3, 4 and 5, the spring clip 7 is engaged over the head 6' of the tool 6 and is held in place by the tension of its side members engaged in the channel 6'' of the tool. The sides of that form of my clip depicted in 10 Figs. 3, 4 and 5, are substantially the same as shown in Figs. 1 and 2 with the exception that the bulged or raised portions 13 are disposed longitudinally instead of transversely and that the flat surfaces 14 cam 15 directly against the adjacent sides of the tool 6. The portion of the supporting arms 11 employed in connection with that form of my clip now being described is substantially the same as that in connection with 20 the other form of clip 7.

The arms 11 both have a shoulder or projection 15 formed on their extreme inner ends and abut against the adjacent enlargement 10 or 13 to prevent the accidental dislodgment of the arms 11, and when it is desired to place the tool 6 in a container or use the same unhindered by the supporting arms 11, the same are folded against the sides of the tool, as depicted in Figs. 1, 4 30 and 5, in either case the supporting arms 11 being held in position by the tension of the clips 7 binding the flattened sides against the tongue 9 or the tool 6.

What I claim as my invention is:

35 1. A device of the class described comprising a substantially U-shaped member connectible to a tool member, and a supporting member carried thereby and extendable laterally to support the tool member.

2. A tool rest of the class described comprising an attaching member connectible to a tool member, and a pair of supporting members carried by the attaching member and movable to extend laterally from the sides of the tool member to support the same 45 in a substantially upright position.

3. A tool rest of the class described comprising an attaching clip connectible to a tool member and having struck out portions, a pair of supporting members having their inner ends rotatably mounted in said struck out portions and having their outer ends extending laterally from the sides of the tool member to support the same in a substantially upright position and movable to 55 a position adjacent the sides of the tool member, and means for retaining the supporting members in either of said two positions under tension.

4. A tool rest of the class described comprising an attaching clip connectible to a tool member and having struck out portions, a pair of supporting members having their inner ends rotatably mounted in said struck out portions and having their outer ends 65 extending laterally from the sides of the tool member to support the same in a substantially upright position and movable to a position adjacent the sides of the tool member, flattened portions formed on said 70 supporting members near their inner ends, and means coöperating with said flattened portions to retain the supporting members in either of said two positions.

In testimony whereof, I affix my signature.

ELMER S. GROSS.
